UNITED STATES PATENT OFFICE.

WILLIAM S. FORD, OF LOUISVILLE, KENTUCKY.

PRESS.

SPECIFICATION forming part of Letters Patent No. 311,824, dated February 3, 1885.

Application filed December 13, 1884. (No model.)

To all whom it may concern:

Be it known that I, W. S. FORD, a citizen of the United States, residing at Louisville, in the county of Jefferson and State of Kentucky, have invented certain new and useful Improvements in Presses; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a side view of my device. Fig. 2 is an end view of the same. Figs. 3, 4, 5, 6, 7, and 8 are detail views. Fig. 9 is also a side view. Fig. 10 is an end view; and Figs. 11, 12, 13, 14, and 15 are detail views.

The invention relates to presses for tobacco, cotton, and similar fibrous substances, and has for its object the construction of such a press, which, while capable of doing more efficient work than those in ordinary use, may be cheap, simple, strong, and easily taken apart for transportation and set up for use.

The invention consists in constructing and arranging the parts in the manner hereinafter described.

In the accompanying drawings, A represents the head-block of the press, made preferably of seasoned timber, and composed of the two equal and similar beams *a a*, lying side by side, and secured together at each end by a rectangular metallic band, hereinafter more fully described, the ends of the beams *a* being rabbeted to receive the band. The pieces *a a* are kept a suitable distance apart, and are tightened in their end beams by having properly-shaped similar wedges, *a' a'*, inserted or driven between them at equal distances from each end and near the end bands.

B is a block of cast metal, fixed centrally to the lower surface of the head-block by means of an upward extension which fits and is properly secured in opposite recesses in the beams *a a*. This block is internally threaded centrally, for a purpose hereinafter explained. The block B is provided with flanges to engage the lower surfaces of the beams *a a*, and assist in keeping the block in place, and also with dovetailed lugs, which engage the outer

sides of said beams and aid in preventing the block from falling downward.

C C are similar retaining-rods passing vertically between the beams *a a*, in opposite recesses in the same, and at equal distances on each side of the block B. The function of these rods is hereinafter explained.

D D are the rectangular end bands which bind the beams *a a* together. These bands have on the upper and lower corners of each side the lugs *d d*, internally threaded to accommodate the threaded upper ends of the rods which bind the head-block to the base of the press, instead of using the bands D. The ends of the beams *a* may be left square as they come from the mill, and properly-shaped cast-iron plates D' may be placed on top and below their ends, the upper one having side lugs which clasp the outside of the beams, as shown. The rods F pass through the extended edges of said plates, and the lower one is secured to the beams *a a* by the bolts *d' d'*. These bolts are alone sufficient to keep the beams *a* apart. By means of these lugs and proper nuts, *d' d'*, the said rods are secured to the head-block and are rendered slightly adjustable in a vertical direction thereon.

E is the base or bed-plate of the press, made preferably of seasoned timber, and composed of the side beams, *e e*, lying parallel to the beams *a a*, and bound together by proper cross-beams, and a central platform, *a' a'*, raised somewhat above the level of the beams, to receive the bottom of the packing hogshead or cask, and prevent the chines of the same from being broken by coming into contact with any part of the base, the platform lying within the chines. The outward-extending ends of the beams *e e* are rounded for the purpose of being inserted into the ring-shaped lower ends of the connecting-rods F.

F F, &c., are four connecting-rods having their upper ends threaded to engage the lugs *d* of the bands D, and their lower ends, *f f*, made ring-shaped to fit over and turn on the rounded ends of the beams *e e*. By this construction the said connecting-rods may be detached from the beam *e* on one side, and the head-block may be turned, when desirable, outward to the other side, the connecting-rod on the latter side rotating on the beam *e*, to which they are attached.

G is the hogshead, barrel, or cask into which the material is to be packed. The said receptacle stands upon the platform a' , as described.

5 H is a stout screw, made of cast metal, and passing through and engaging the internal thread of the cast-metal block B. The upper end of the screw is made into or has fixed upon it the transverse socket h , into which fits the 10 end of the lever h' , by which the screw is actuated. In practice the sockets extend to both sides, so as to accommodate the opposite levers, as shown. The screw is made short, so that the levers may not be out of reach when 15 it is elevated to full height. The lower end of the screw is rounded, and sets against a properly-shaped metallic socket, h^2 , which rests or is fixed upon the follower or packing-bars when the press is in action. The point 20 of the screw is chilled, case-hardened, or made of steel to prevent rapid wear, and works in a chilled socket, and the screw is made hollow, so as to give it lightness while retaining sufficient strength.

25 I is the follower, which rests directly upon the material which is to be packed, and i are tiers of packing-bars lying in ascending pairs, each pair being transverse to the one immediately below.

30 i' is a single central bar lying across the highest tier, and carrying the socket h^2 , as shown.

35 J J are similar eccentric cams, having their pivot points or journals cast upon them, and rotating in the space between the beams a , in proper recesses in which the said journals turn. The said cams have each a depending arm, j , and each is situated immediately to the outer side of one of the retaining-rods C, 40 with its edge bearing lightly against the same, so that when the rod attempts to ascend the cam turns and binds against it and stops its motion. When released from the rod, the arm j brings the cam into normal position. Sometimes it is desirable to use a rectangular packing-case having one or more sides hinged or 45 detachable. In that case the receptacle K has the securing-slips k fixed to beams on its hinged or detachable side or sides, and the retaining-hooks k' pivoted to proper brackets, 50 secured to similar bands on its fixed sides, the lower end of the cam resting within and between proper retaining-slips secured to the upper surface of the base, as shown in the drawings.

55 The method of packing is as follows: As the screw is driven down the retaining-rods C accompany it, sliding freely in the recesses or channels in the head-block; but when the 60 screw is elevated and the swelling or recoil of the pressed material attempts to force the retaining-rods upward the cams are turned against them and hold them down, the bearing between the two being sufficient for this 65 purpose. The retaining-rod on one side is then raised by hand, its cam being pulled and held down, and the material inserted and

70 packed under the follower from that side. The screw is then again brought to act and the material again pressed, the next packing 75 being done on the opposite side from the first.

When desirable, as in putting in the first part of the material, the connecting-rods on one side may be detached from the base and the head block rotated to the other side. This gives 80 more room. The rounded ends of the beams e are generally tapered, so as to allow the ring-like ends of the connecting-rods to be easily fitted over them.

85 The advantages of the invention are, that the press can be cheaply made, can exert powerful force, is compact and comparatively light, can be knocked down for transportation very quickly, occupying little space when packed, and can be quickly set up and adjusted for operation.

Having thus described my invention, what I desire to secure by Letters Patent is—

1. A press for tobacco or other material, composed of a head-block having properly 90 fixed thereto a cast-metal block provided with an internally-threaded vertical opening, a cast-metal operating-screw engaging the opening in said block, a base-piece of proper construction, and rods or bars suitably constructed and arranged to connect and firmly bind together the said head-block and base-piece, 95 substantially as specified.

2. In a press for tobacco or other material, the combination of a head-block composed of 100 two similar opposite beams bound together at their ends by metallic straps or bands, and properly-shaped wedges inserted or driven between the said beams, so as to keep them tight in their end bands, while having a space 105 between them, with a metallic block fixed centrally between said beams, and having an internally-threaded opening, a properly-actuated operating-screw engaging said opening, a bed or base piece, and rods or bars properly 110 constructed and arranged to connect and firmly bind together the said base-piece and head-block, substantially as specified.

3. In a press for tobacco or other material, the combination of the head-block A, composed of the side beams, a , united at their 115 ends by the bands or straps D, the wedges a' , and the metallic block B, with a properly-constructed base-piece provided with a central platform having an elevation above the 120 rest of the base, and rods or bars connecting the said base and head-block together, substantially as specified.

4. The combination, in a press for tobacco or other material, of the head-block A, composed of the two similar beams a , and the bands and straps D, with the wedges a' , and a cast-metal block situated centrally between the beams a , provided with an internally-threaded opening, and having proper flanges 130 to bear against the lower surfaces of the beams a , and dovetailed lugs to bear against and engage the outer sides of the same, substantially as specified.

5. In a press for tobacco or other material, the combination, with a base-piece, a head-block, and rod constructed and arranged to connect the same and bind them together, of 5 two or more retaining-rodsl sliding easily through channels in the head-block, and having their lower ends resting upon the apparatus to press the material acted upon, and an equal number of eccentric cams or rollers turning or pivoted in the head-block in such manner as to permit the descent of the retaining-rodsl but stop their ascent, substantially as specified.
6. In a press for tobacco or other material, 10 the combination of the head-block A and base-piece E, properly connected thereto, with the retaining-rodsl C C and eccentric cams J, substantially as specified.
7. In a press for tobacco or other material, 15 the combination, with the head-block A and bands or straps D, of the base-piece E, provided with the beams e e, having their ends rounded and slightly tapered, and the connecting bars or rod F, having the ring-shaped lower ends or eyes, f, substantially as specified.
- 20 25 8. The combination, with a tobacco or other
- press, composed of a head-block and base-piece properly constructed, of a removable baling-box composed of a base-piece and detachable 30 sides, the latter resting within proper slips attached to the former, and secured together, when set up, by the slip k and hook k', pivoted to the bracket k², substantially as specified.
9. In a tobacco or other press, the combination of the head-block A, bands D, connecting-rodsl F, base-piece E, and cast-metal block B with the retaining-rodsl C, eccentric cams J, and screw H, acting upon the socket h², which is upheld to the packing-bars i i and follower I, 35 40 substantially as specified.
10. In a press for tobacco or other material, the combination, with the beams a, forming the head-block, and upper and lower plates, D', of the rods F and bolts d², passing through the 45 lower plate, D', and entering the beams a, substantially as specified.

In testimony whereof I affix my signature in presence of two witnesses.
